UNITED STATES PATENT OFFICE.

BENJAMIN W. GOODING AND GEORGE GOODING, OF PLYMOUTH,
MASSACHUSETTS.

DESIGN FOR A HANDLE FOR SPOONS, &c.

SPECIFICATION forming part of Design No. 28,885, dated June 21, 1898.

Application filed August 19, 1897. Serial No. 648,833. Term of patent 7 years.

To all whom it may concern:

Be it known that we, BENJAMIN W. GOODING and GEORGE GOODING, citizens of the United States, residing at Plymouth, in the 5 county of Plymouth and State of Massachusetts, have invented a new and original Design for a Handle for Spoons, Forks, and Similar Articles, of which the following is a specification, reference being had to the accompanying drawing, forming part thereof.

The drawing represents in top view a handle for spoons, forks, and similar articles, showing our design.

The leading feature of our design for a handle for spoons consists in the representation in raised or struck-up figures or bas-relief, the standing figure of Myles Standish dressed in Pilgrim costume and girt, with his famous sword, immediately below the figure of Myles 15 Standish being the representation of John Alden and Priscilla Mullins dressed in Pilgrim costume and seated at a spinning-wheel, the remaining narrow portion of the handle 20

being ornamented with the vine of the May-flower or trailing arbutus, around which is a 25 spirally-twisted scroll which provides space for any suitable words, the whole intending to portray the idea of Longfellow's famous poem "The Courtship of Myles Standish." The figure *a* of Myles Standish is represented 30 between two trees, the whole inclosed with scroll-like ornaments, and figure *b* represents John Alden and Priscilla seated at the spinning-wheel. The remaining narrow portion of the handle *c* is provided with ornamentation of May-flower vine entwined with a scroll, which provides space for any suitable words.

We claim—

The design for a handle for spoons, forks and similar articles, substantially as herein 40 shown and described.

BENJAMIN W. GOODING.
GEORGE GOODING.
